UNITED STATES PATENT OFFICE.

CALEE E. SUMMERS, OF DETROIT, MICHIGAN, ASSIGNOR TO GENERAL MOTORS RESEARCH CORPORATION, OF DETROIT, MICHIGAN, A CORPORATION OF DELAWARE.

OIL RECTIFIER.

Application filed June 5, 1928. Serial No. 113,934.

This invention relates to oil distillation apparatus of the type now employed upon automobile engines to purify the oil during the operation of the engine. The device 5 forming the subject of this application includes a number of novel features and the method of distillation employed involves certain novel steps. Among these is the provision for carrying out distillation in a 10 non-oxidizing atmosphere. While other gases may be employed to produce the non-oxidizing atmosphere, for simplicity I have preferred to make use of a portion of the exhaust gases employed to heat the still. 15 These gases are preferably passed through the still so as to carry away distillates and at the same time impart heat to the oil, thereby assisting in distillation. Indeed, if desired, the gases directly contacting with 20 the oil may constitute the sole heating agent, although I prefer to also employ an exhaust jacket for the still.

To control the heating of the still I have provided a suitable valve controlling the 25 flow of exhaust gases about the still. For simplicity this valve may be operated by link connection with the throttle so that as the throttle is opened the valve will be moved toward closed position to prevent 30 overheating of the oil when the engine is working under conditions of heavy load or high speed. This valve is preferably of such design as to shut off the flow of gases over the oil as well as through the jacket.

I have also provided novel means for insuring sufficient flow of exhaust gases to the still to raise the oil to the desired temperature. This means consists of a device projecting into the exhaust manifold for diverting a portion of the gases about the still, and, if desired, an aspirator operated by the exhaust gases and serving to withdraw the gases from about the still. I have also provided novel means for removing 45 diluents from the distillation chamber. This consists of a conduit leading from the top of the chamber to a point adjacent the air intake of the usual carburetor. The gases in this conduit are subjected to the aspirating action of the air entering the carburetor intake rather than to the vacuum existing in

the manifold passages so that the suction applied to the still varies in accordance with the flow of air into the carburetor.

Novel constructional details are also employed in the device herein disclosed, such as the arrangement whereby the hot exhaust gases and lubricating oil pass through the still in opposite directions, the provision of barriers in the distillation chamber whereby a tortuous passage is provided for the lubricating oil; and other features to be later described.

On the drawing:

Figure 1 is a side elevation of an engine 65 having my oil rectifying device applied thereto, parts being broken away to better show points of construction.

Figure 2 is a longitudinal section through the still.

Figure 3 is a plan view of the still with parts broken away.

The reference character 2 indicates an internal combustion engine having a carburetor 4 and an oil pump 6 located in the crankcase 8 and supplying oil to the bearings in the customary manner. 10 indicates the usual exhaust manifold. My still is indicated generally by the reference character 12. It comprises an inner or distillation chamber 14 and a surrounding jacket 16 for the passage of exhaust gases. A tube 18 extends up from the jacket and establishes communication with the exhaust conduit, the projecting end of the tube being bevelled as 85 shown at 19 to intercept the passing gases and divert a portion of them about the still. At the other end the jacket is provided with a similar tube 20 having its end 21 extending into the exhaust conduit and similarly 90 bevelled, but facing in the direction of the gas flow so that the gases exert an aspirating action upon the end of the tube and assist in moving the gases through the jacket. The distillation chamber is provided with 95 baffles 22 and 24 arranged to afford a tortuous passage for the flow of oil through the chamber.

Oil is supplied to the chamber from the pump 6 through a metering device, indicated at 26, of the type shown and claimed in the application of Charles R. Short and

Charles L. Lee, Serial No. 637,812, filed May 9, 1923. The purpose of the metering device is to restrict the supply of oil to the still so that the oil therein may quickly reach the desired temperature. This metering device consists of a shaft, in this case the usual cam shaft 28, having a hole 30 drilled therethrough, which intermittently registers with passages 32 and 34, the first connected to the pump 6 by suitable tubing and the second to the still. This form of metering device possesses the advantage that since flow of oil to the still is permitted for a short period only during each revolution of the cam shaft, oil conduits and passages of considerable size may be employed, thus avoiding clogging and yet the supply of oil to the still is kept within the desired limits. The means for supplying the still with oil may serve as a pressure by-pass for the pump, or, if desired, a separate by-pass may be provided. The oil enters the still through the fitting 36 and leaves the still through a stand pipe 38 leading to the crankcase.

The wall of the distillation chamber adjacent the conduit 18 is provided with an opening 40 to receive conical valve 42 secured to butterfly valve 44 which controls the passage of exhaust gases into the jacket. These valves may be independently mounted if desired. Butterfly valve 44 is connected to the usual throttle 46 by means of suitable linkage 47 so arranged that as the throttle is opened the valves 42 and 44 are moved toward closed position.

The operation of the device is as follows: A portion of the output of the pump 6 is forced through the metering device, previously described, into the still, the oil entering at 36, following a tortuous passage through the distillation chamber, and returning to the crankcase through the stand pipe 38. Exhaust gases flowing through the manifold 10 are intercepted by the bevelled end 19 of the conduit 18 and led to the still. A portion of the intercepted gases enter the distillation chamber through the port 40, follow a zig zag course through the chamber in a direction opposite to the direction of oil flow entraining diluents with them, and are finally discharged through conduit 50 leading to a point adjacent the air intake 52 of the carburetor 4. Gases entering the jacket 16 are drawn into the exhaust manifold by means of the suction produced by the flow of gases past the bevelled end 21 of the conduit 20. It will be noted that the oil is heated by the gases flowing through the distillation chamber as well as those flowing through the jacket. The operation of the still is controlled by means of the connection 47 between the valves 42-44 and the throttle 46 so that the percentage of exhaust gases diverted about the still is re-

duced when the engine is operating at high speeds or under heavy loads. By this means substantially uniform heating of the still is obtained under varying operating conditions. 70

I claim:

1. The combination of an internal combustion engine provided with the usual intake and exhaust and embodying a lubricating system, and means for exposing a portion of the oil in the system to the direct action of hot gases from the engine exhaust to effect vaporization of diluents. 75

2. The combination of an internal combustion engine provided with the usual intake and exhaust and embodying a lubricating system, a distillation chamber, means for passing oil from the system through the chamber, means for exposing the oil in the chamber to the direct action of hot gases from the engine exhaust to effect vaporization of diluents. 80

3. In the combination as defined in claim 2, and means for controlling the application of the hot gases to the oil. 90

4. The combination of an engine embodying a lubricating system, a distillation chamber, means for passing oil from the system through the chamber, means for heating the oil in the chamber, and means for maintaining a non-oxidizing atmosphere in the chamber. 95

5. In the combination as defined in claim 4, said last named means comprising means for introducing exhaust gases into the chamber, and means for withdrawing the gases together with entrained diluents therefrom. 100

6. The combination of an internal combustion engine embodying a lubricating system, a distillation chamber, means for passing oil from the system through the chamber, means for heating the oil in the chamber, means for producing a flow of non-oxidizing gases through the chamber in contact with the oil, and common means for controlling the heating of the oil and the flow of the last named gases. 105

7. The combination of an engine embodying a lubricating system, a distillation chamber, means for passing oil from the system through the chamber, means for passing exhaust gases about the still to heat the oil therein, and means for introducing hot exhaust gases into the chamber, and removing them therefrom together with entrained diluents. 115

8. In the combination as defined in claim 7, said engine being provided with the usual throttle valve, and means for controlling the passage of exhaust gases to the still inversely with the throttle opening. 125

9. An engine having a lubricating system, a distillation chamber, means for passing oil from the system through the chamber, and means for passing an evaporative flow of 130

hot gases through the chamber in a direction opposite to the direction of oil flow.

10. The combination of an engine having a lubricating system, a distillation chamber,

5 means for passing oil from the system through the chamber, a jacket for said chamber, means for supplying the jacket with gases from the engine exhaust, and means establishing communication between the

10 jacket and the chamber to permit exhaust gases to enter the still in contact with the

lubricating oil, and common means for controlling the flow of gases about the jacket and the communication between the jacket and the chamber.

15

11. In the combination as defined in claim 10, said engine being provided with the usual throttle, and said last named means varying inversely as the throttle opening.

In testimony whereof I affix my signature.

CALEB E. SUMMERS.
